[57] CLAIM

The ornamental design for a felt pen, as shown and described.

DESCRIPTION

FIG. 1 is a top, left front perspective view of a felt pen showing my new design;

FIG. 2 is a left side elevational view, the right side being a mirror image thereof;

FIG. 3 is a front elevational view;

FIG. 4 is a rear elevational view;

FIG. 5 is a top plan view;

FIG. 6 is a bottom plan view;

FIG. 7 is a perspective view in an exploded condition;

FIG. 8 is a typical side elevational view of the pen body with the cap member removed for convenience of illustration;

FIG. 9 is a top plan view of FIG. 8;

FIG. 10 is a bottom plan view of FIG. 8;

FIG. 11 is a left side elevational view of the cap member with the pen body removed for convenience of illustration;

FIG. 12 is a top plan view of FIG. 11;

FIG. 13 is a bottom plan view of FIG. 11; and,

FIG. 14 is a cross-sectional view of FIG. 1.
